(57) **CLAIM**

The ornamental design for a nasogastric tube securement device, as shown and described.

DESCRIPTION

FIG. 1 is a front perspective view of a first embodiment of a nasogastric tube securement device, showing the new design;

FIG. 2 is a top plan view thereof;

FIG. 3 is a bottom plan view thereof;

FIG. 4 is a front side elevational view thereof;

FIG. 5 is a rear side elevational view thereof;

FIG. 6 is a right side elevational view thereof; and

FIG. 7 is a left side elevational view thereof.

FIG. 8 is a front perspective view of a second embodiment of the nasogastric tube securement device, showing the new design;

FIG. 9 is a top plan view thereof;

FIG. 10 is a bottom plan view thereof;

FIG. 11 is a front side elevational view thereof;

FIG. 12 is a rear side elevational view thereof;

FIG. 13 is a right side elevational view thereof; and,

FIG. 14 is a left side elevational view thereof.

(Continued)

The broken line showing illustrates the non-claimed features within the design for the claimed article of manufacture.
